EXTENSION DEVICE FOR COLLARS

Max Goldschmidt, Meiningen, Germany

Application June 29, 1934, Serial No. 732,987
In Germany October 25, 1933

4 Claims. (Cl. 2—141)

This invention relates to extensible fastening devices for collars and while the invention is primarily adapted to collars attached to shirts, it is capable of use in connection with any collar.

5 Shirts with collars attached are universally sold in half sizes and thus are frequently not a perfect fit for the majority of wearers. Moreover, such collars shrink in washing and eventually become too tight.

10 The principal object of this invention is an adjustable and extensible connection for the ends of a collar so that it may be fastened about the neck of the wearer with the requisite snugness. Accordingly, one side of the collar is provided with

15 an elongated tab or strap upon which may be adjustably and, preferably, removably, positioned one of a pair of cooperative fastening devices, such as a male snap fastener, the other device of the pair being fixedly positioned on a tab or on the free end of the neck band of the collar.

20 Another object of the invention is an extensible fastening device of the character described which shall conform to the neck of the wearer. In accordance with this aspect of the invention the strap or tabs are curved, preferably on an arc commensurate with the curvature of the edge of the collar.

25 The invention also seeks adjustable carrying devices for the cooperative fastening member. To this end, a slide may be provided formed with spaced slots through which the strap passes. In another of its aspects, the cooperative fastening member may be carried with a spring clip or clamp through which the strap may pass and be clamped thereby.

30 An attractive feature of the invention resides in the provision of ornamentation masking the character of the fastening device. A pearl button or simulation thereof, may be carried outwardly of the slide or clip to simulate the usual shirt button.

35 For convenience in manipulation, the strap may be slotted at one or a plurality of points, through any one of which slots the snap fastener member or button may pass or be accessible.

40 These and other objects of the invention and the means for their attainment will be more apparent from the following detailed description, taken in connection with the accompanying drawings illustrating various embodiments by which the invention may be realized and in which;

45 Fig. 1 is a view, in perspective, showing a collar, to which the invention is applied.

50 Fig. 2 is a view, looking from the front and showing a slide to which a button is affixed.

Fig. 3 is a view showing the rear side of the slide of Fig. 2.

Fig. 4 is a view showing the slide looking from the above and

Fig. 5 is a view showing a modified form of slide.

Fig. 6 is a front view of the slide of Fig. 5.

The collar 7 may be of any desired kind or shape, having the neckband 8. To one end of the neckband, preferably that corresponding to the side of the shirt opening in which the button hole is made, is a tab 10 which may in fact be an extension of the neckband. To this is attached, on the outer side, one of a pair of cooperative fastening devices, such as the male member 12 of a snap fastening device.

10 At the other end of the collar or neckband thereof is formed or attached a strap or elongated tab, 14, of any length and suitable width desired upon which is adjustably carried a slide, 16, which, in Fig. 1, is shaped to represent a buckle. That is, it may be formed with spaced slots, 17, through which the strap passes, suitable provision being made for holding the strap within the slots, 17, as by roughening, not shown, on opposed edges thereof. On the rear of the slide 16, is carried the 15 companion fastening device, illustrated as the female member, 19, of the snap fastener.

20 It is preferred that the strap, 14, and/or the tab 10, be curved to correspond with the curvature of the edge of the collar, that is, the edges, 20, of the strap be curved, on a curvature commensurate with the curvature of the edge 21, whereby the collar more nearly fits the neck of the wearer. It is desirable that the strap be so shaped and/or positioned with respect to the neckband that the 25 point of fastening shall hold the overlapping neckband portions, in the front, in place.

25 Figs. 2 thru 5 illustrate slides masked by an ordinary pearl button, 26. This, broadly, may be any sort of ornamental device or simulation thereof. Thus, in Figs. 2, 3 and 4, the slide, 23, is provided with slots, 24, so that the strap, 14, passes from the outside thru one slot, 24, behind the slide and passes again to the outside of the slide through the other slot, 24. In this instance, the 30 strap, 14, may be formed with one or a plurality of slots 25 (Fig. 3) whereby the snap fastener member, 19, may be exposed, as by projecting therethru. Obviously, the strap may pass from the rear, across the front, as in Fig. 1, the button, 26, then passing thru the slit, 25, or a button hole, 50 as will be understood.

35 In lieu of a slide on the order of a buckle, as described, the slide, as shown in Figs. 5 and 6, may take the form of a spring clip, S-shaped in cross-

section or reversely bent of resilient metal. The snap fastening member 19, or other fastening means, may be carried on one leg 28, while the strap conveniently passes between the other free leg 29 and the mid-portion 30 by which it is firmly but removably clamped. If desired, a button, 26, or other ornamentation may be carried on the outer face of the reversely bent spring clamp, 28-30.

10 If desired, the face of member 29 may be colored, as may also the slides illustrated in Figs. 1 and 2, as by an enamel, in any color desired. Such color may be the same as or different from that of the strap 14, which, of course, is preferably of the same material and color as the shirt.

15 The use and adjustment of the adjustable fastening device of this invention will be apparent from the foregoing description. Suffice it to say that the slide 16, 23 or 28-30 may be moved along 20 the strap to the desired position and the fastening device thereon engaged with the companion fastening device carried with the other end of the neckband until the collar is properly adjusted to the neck.

25 If desired, a loop, 31, may be placed on the free end of the neckband proper, thru which the end of the strap-like portion, 14, may pass when the collar is worn open at the neck.

30 Various modifications will occur to those skilled in the art in the composition, configuration and disposition of the component elements going to make up the invention as a whole and no limitation is intended by the phraseology of the foregoing description or illustrations in the accompanying drawing except as indicated in the 35 appended claims.

What is claimed is:—

1. In a collar, in combination, a flexible fabric strap with arcuate edges carried with one end 40 of the collar neck band, a cooperative fastening

member carried with the other end of the collar neck band, a companion fastening member and means to adjustably and removably secure the last named fastening member to the strap, said strap being curved in a vertical plane on a radius 5 commensurate with the curvature in a vertical plane of the neck band of the collar whereby the point of fastening holds the overlapping neckband portion in place.

2. In a collar, in combination, a strap carried 10 with one end of the collar, a cooperative fastening member carried with the other end of the collar, a slide having spaced portions between which the strap passes, said strap overlying a rearwardly disposed central face of the slide, a companion 15 fastening member carried on a rearwardly disposed face of the slide, a forwardly disposed portion having the representation of a button or like ornamental means depicted thereon to mask the forwardly disposed portion of the slide. 20

3. In a collar, in combination, an inelastic strap one end of which is secured to one end of the collar, a cooperative fastening member carried with the other end of the collar, a slide comprising 25 a reversely bent spring clamp through one fold of which the strap passes, and a companion fastening member carried with the rear side of the slide for engagement with the first named fastening means.

4. In a collar, in combination, a strap carried 30 with one end of the collar, a cooperative fastening member carried with the other end of the collar, a slide formed with slots defining a cross-bar therebetween through which slots the strap passes 35 behind the cross-bar and a companion fastening member carried with the cross-bar of the slide, said strap being slotted and the fastening member on the slide normally passing through the slot. 30
